UNITED STATES PATENT OFFICE

HARRY V. MARSH, OF CHICAGO, ILLINOIS

SWINGING SIGN

Application filed March 21, 1929. Serial No. 348,771.

The present invention relates to an advertising device formed of a single blank and adapted to comprise two independent sections, one of a circular configuration, and the other a plane surface in association therewith and locked in a predetermined position upon the circular section which latter section provides the base for the device.

The device may be employed for a counter display or it may be employed as a hanging display.

Included in the objects of the invention is a new and novel arrangement of sections of a blank for the purpose of forming a combination of circular and flat advertising display matter; the provision of a novel combination of flat and circular display placards, and the combination in a display device of a portion depicting a can or other circular 20 device and the remainder or second portion comprising a placard supported thereby or dependent therefrom.

These objects, and such other objects as may hereinafter appear, are obtained by the 25 novel combination, the unique arrangement, and the improved construction of the several sections or elements shown in the single embodiment of the invention illustrated in the accompanying drawings, and in which:

Figure 1 is a plan view of the blank employed for forming the device illustrated in Figure 2;

Figure 2 is a front elevation of the articulated blank;

Figure 3 is a transverse section just above the central portion of the device; and

Figure 4 is a reduced elevation of the device used as a swinging sign.

Like reference characters are used to designate similar parts in the drawings and in the description which follows.

Reference should be had first to Figure 1, but in conjunction therewith, Figures 2 and 3 may be conjointly read.

The circular portion of the device is formed by the main body thereof indicated by the reference 10, which portion extends from the extension 11 at the left hand side of the figure to the enclosed tongue 12 at the right hand side thereof. The tongue 11 is adapted

to be inserted through the opening used to form the enclosed tongue 12 whereby to provide an interlock in the circular part of the device with the right hand portion 13 (Figure 1) diametrically disposed within the circular portion formed of section 10. Thus, a truly circular display device is formed and in which there is a centrally disposed spacer member having a flat placard section extending therefrom.

The lower edge of the blank is adapted to be cut along a straight line so that the device will have a truly level bottom when seated upon a counter. For providing an interlock at the bottom, an extension hook 14 is provided upon the spacer 13, and this is adapted to be inserted into the slit 15 extending from a point on the lower edge of the blank intermediate the tongue 12 and the extension 11.

The upper section of the blank (Figure 1) depending from spacer 13 is divided into a part 16. Depending from section 16 is a second section 17, there being a score 18 therebetween to facilitate the folding of the section 17 flat upon the back of the member 16.

Member 16 extends to the right sufficiently that the member 17 exactly coincides and registers therewith, or in other words, members 16 and 17, from score 18, are of equal length and are divided equally and one from the other by said score 18.

Adjacent the top edges of section 13, there are ears 19 and 20 upon the member 16. The body of the ear 19 is formed for the irregular slit employed by slitting the member 16 apart from the main body 10.

Upon said main body 10, and substantially half way between tongue 11 and tongue 12 is an extension 21 in the upper edge of said body, and in which is V-shaped slit 22. Opposite thereto and on the member 17 is a complementary depression which serves no purpose in interlocking the parts.

On the member 17, however, is an extension 23 having a V-shaped slot 24 therein.

The extension 23 is adapted to be inserted into the slot 22, the slot 24 facilitating the interlock between the members 10 and 17.

One die cut extends from the extreme end 100

of member 17 to and about the ear 19 and this cut divides the part 10 from the part 17, and coincidentally forms the reversed extensions 21 and 23 and the slits or notches 22 and 24.

5 An added extension 25 with a notch 26 may be provided in body 10 to interlock with ear 19, but this is optional.

When assembly is desired, as has been 10 previously indicated, the tongue 11 is adapted to be inserted through the slot whereby there is formed the flap 12, the part 13 then extending diametrically across the circular section thus formed, with the ear 14 interlocking into 15 slit 15.

Thereupon the member 17 is folded back- 20 wardly upon the member 16, the ear 20 being adapted to be inserted in the notch 22, in extension 21, and the ear 19 being adapted to be inserted into the slit 26 in the extension 25. The ear 20 is also adapted to be inserted into slots 24 in the extensions.

25 In this manner, a complete and rigid assembly of the device is obtained. The circular member is securely locked both at its bottom and at its top.

Likewise, the laminated flat display placard at the top is secured with its two laminations thereof in close proximity and free from 30 the possibility of accidental separation.

When the device is used as a hanging sign, a string 27 is inserted at the upper edge and near the center of member 13, thus providing for balanced hanging of said placard, 35 with the circular portion uppermost as shown in Figure 4, the panels 13 and 17 being below the circular section.

I claim:

1. A placard formed from an integral 40 blank and comprising a truly cylindrical display section and a flat display section transversing said cylindrical section.

2. A placard as described in claim 1, and having a spacer diametrically disposed in 45 said cylindrical section.

3. A placard formed from an integral blank and comprising a rectangular section adapted when folded to provide a substantially cylindrical display section, and a sec- 50 ond section providing a flat display section adapted to traverse said cylindrical section when rolled, and in which a portion of said second section forms a spacer extending across said rectangular section when rolled 55 into a cylinder.

4. A placard formed from an integral blank and comprising a rectangular section adapted when folded to provide a substantially cylindrical display section, a second sec- 60 tion providing a flat display section adapted to traverse said cylindrical section when rolled, and a spacer diametrically co-exten- 65 sive with said cylindrical part, said second section being an extension of said spacer.

5. A blank comprising a main body which

is adapted to be rolled into a cylinder, said main body having interengaging portions for locking the ends of said blank when in such cylindrical form, there being an extension at one end of the cylinder forming portion of 70 said blank to provide a spacer extending diametrically across the cylinder formed from said body.

6. A blank comprising a main body which is adapted to be rolled into a cylinder, said main body having interengaging portions for locking the ends of said blank when in such cylindrical form, there being an extension at one end of the cylinder forming portion of 75 said blank to provide a spacer extending dia- 80 metrically across the cylinder formed from said body, said spacer having an extension portion adapted to form a flat placard projecting out of said main body when said main body is rolled into a cylinder.

7. A blank comprising a main body which is adapted to be rolled into a cylinder, said main body having interengaging portions for locking the ends of said blank when in such cylindrical form, there being an extension at 85 one end of the cylinder forming portion of 90 said blank to provide a spacer extending dia- 95 metrically across the cylinder formed from said body, said spacer having an extension portion adapted to be articulated to provide a two-faced transversely disposed laminated flat display space.

8. A blank comprising a main body which is adapted to be rolled into a cylinder, said main body having interengaging portions for locking the ends of said blank when in such cylindrical form, there being an extension at 100 one end of the cylinder forming portion of 105 said blank to provide a spacer extending dia- 110 metrically across the cylinder formed from said body, said spacer having an extension with parts adapted to provide a transversely 115 disposed display space and adapted to interlock with the material of said body when rolled into cylindrical form.

9. A blank comprising a main body which is adapted to be rolled into a cylinder, said main body having interengaging portions for locking the ends of said blank when in such cylindrical form, there being an extension at one end of the cylinder forming portion of 120 said blank to provide a spacer extending dia- 125 metrically across the cylinder formed from said body, said spacer having an extension adapted to be articulated to provide a transversely disposed laminated placard, each lamination of which is adapted to be disposed in interlocking engagement with the material of said body when the latter is rolled into a cylinder.

10. A display device formed from an integral blank rolling one section thereof and by articulating a second section thereof, the assembled device comprising a flat display portion, a cylindrical display portion adj-

cent thereto, and a spacer in said cylindrical portion maintaining said flat portion in the assembled device in a plane diametrical to said cylindrical display section.

5 11. A display device formed from a blank one half section of which is rolled into a cylinder, and having a second half section parallel thereto which interlocks with said cylinder and provides a flat display part not 10 materially overlapping said cylindrical section.

12. A display device comprising a blank having one section adapted to be rolled into a cylinder, and having a second section interlocking with said first section when the latter is rolled into a cylinder, said second section comprising laminations formed by articulating the material of said blank, each of said laminations being adapted to interlock with said cylindrical part and providing a flat display part not materially overlapping said first section when the latter is 20 rolled into a cylindrical form.

13. A display device of a single sheet of material and comprising a cylinder, a spacer thereacross, and a flat display section diametrically disposed to said cylinder and at one end thereof, there being interlocking sections intermediate said cylinder and said 30 flat section.
